UNITED STATES PATENT OFFICE.

ALFRED SWENSEN, OF RIVERSIDE, ILLINOIS.

WASHING MACHINE.

Application filed June 20, 1921. Serial No. 478,778.

My invention relates to washing machines.

One of the principal objects of my invention is to provide an improved washing machine which will impart a movement to the clothes and water which will result in a thorough cleansing of every part of each piece of clothing contained therein without injury.

A further object of my invention is to provide an improved power-driven washing machine provided with means for disconnecting the oscillatable tub from the driving mechanism and bringing the oscillatable tub to rest in a definite position.

15 A further object of my invention is to simplify the driving mechanism for the washing mechanism and wringer.

20 A further object is to provide an improved washing machine which will be simple in construction, durable and efficient in use, safe and easy to operate.

25 Further objects will appear from the detailed description to follow and from the appended claims.

30 In the drawings in which several embodiments of my invention are shown,—

Figure 1 is a vertical sectional view showing a washing machine;

35 Fig. 2 is a sectional view of the tub substantially on the line 2—2 of Fig. 1;

Fig. 3 is a perspective view of the tub with parts broken away to show the interior construction;

40 Fig. 4 is a view corresponding to Fig. 3 but showing a different form of oscillatable tub;

Fig. 5 is a section on the line 9—9 of Fig. 4.

45 Referring first to Figs. 1 to 3 inclusive, the construction shown therein comprises an oscillatable tub 15, in which the clothes are placed, a wringer construction 16, an electric motor 17 for driving the tub 15 and wringer 16, transmission mechanism 18, between the motor 17 and the tub 15 and wringer 16, and a frame-work 19 for supporting the tub 15, wringer 16, motor 17 and transmission 18.

50 One of the important features of my invention is the provision of means whereby as the clothes are caused to move back and forth they are also caused to rotate as a mass about a substantially vertical axis, the combined motion being a sort of to and fro movement combined with a whirlpool movement.

55 In the construction shown in Figs. 1 to 3 inclusive, this is effected by the provision of

a pair of projections 20 and 21 inside the tub 15, located on opposite sides of the tub. As shown in Fig. 4, each of these projections 21 has a gradually inclined upper face 22 which permits the clothes to slide easily therealong as the tub oscillates, and an abrupt shoulder portion 23 back of which a portion of the mass of clothes drops as the clothes reciprocate back and forth in the tub, which abrupt shoulder 23 slightly hinders the return movement of that part of the mass of clothes engaged by it.

As indicated by the arrows A in Fig. 3, the combined effect of the projections 20 and 21 is to cause a unidirectional rotation of the clothes in the tub about a vertical axis, the unidirectional rotation being combined with a reciprocating movement of the clothes effected by the oscillation of the tub 75 15. This movement of the clothes exposes all parts of the mass to the action of the water which is caused to move back and forth by the movement of the tub, and results in a thorough cleansing of every part 80 of each garment.

The transmission 18 for the tub 15 and wringer 16 comprises a worm 24, driven directly from the motor-shaft 25, and transmission 26 between the worm 24 and the tub 85 15.

The transmission 26 between the worm 24 and the tub 15 comprises a worm-gear 28 meshing with the worm 24, a shaft 29 on which the worm-wheel 28 is mounted, a 90 crank 31 mounted on the shaft 29, and a connecting rod 32 pivotally connected at one end to the crank 31 and at the other end to the oscillatable tub 15.

For stabilizing the action of the oscillatable tub 15 and preventing undue strain due to the reversal of movement, stabilizing coil tension springs 35 may be provided, secured at one end to the frame 19 and at the other end to the oscillatable tub.

100 In Figs. 4 and 5, is shown a different form of tub which can be substituted for the tub 15 shown in Fig. 1. This tub 55 is set at an angle to the shaft 56 on which it is oscillatably mounted, and is provided on its 105 opposite side walls with projecting corrugated members 57 and 58, the effect of which is to impart a whirlpool action to the clothes in addition to the to and fro movement caused by the oscillation of the tub as indicated by the arrows B. As the tub 55 is 110 rocked to move the clothes toward the end

of the tub provided with the corrugated member 57, the clothes are thrown against this corrugated member and retarded in their movement, the other side of the mass of clothes moving forward freely. This tends to cause a movement of the clothes in the direction of the arrows B. Similarly when the mass of clothes is thrown toward that end of the tub provided with the corrugated member 58, the clothes are thrown into engagement with the corrugated member and that portion of the clothes in engagement with the corrugated member is retarded in its movement while the opposite side of the mass of clothes moves forward freely. This also tends to cause a rotation of the mass of clothes in a direction indicated by the arrows B so that the combined result of the corrugated members 57 and 58 is to cause a unidirectional movement of rotation of the mass of clothes about a vertical axis.

Having thus described my invention, what I claim as new and desire to secure by Letters Patent of the United States is:

- 25 1. A washing machine comprising a tub, and means for imparting to the clothes in said tub a back and forth movement, and also a movement of rotation about a substantially vertical axis, said last means comprising two projections, one on each side of the tub, each projection being constructed to allow the clothes in contact therewith to slide past easily in one direction, and having an abrupt shoulder to hinder the movement of the clothes therewith in the opposite direction.
- 30 2. A washing machine comprising a tub, and means for imparting to the clothes in said tub a back and forth movement, and also a movement of rotation about a substantially vertical axis, said last means comprising two projections, one on each side of the tub, each projection having an inclined portion along which the clothes slide easily in one direction, and an abrupt shoulder to hinder the movement of the clothes in the opposite direction.
- 35 3. A washing machine comprising an oscillatable tub, the oscillation of which moves the clothes from one end to the other thereof, and means for imparting a movement of rotation to the clothes about a substantially vertical axis, as they are dashed back and forth, comprising an abrupt shoulder located to one side of the tub, back of which the clothes fall by gravity when they are moved to one end of the tub, and which retards the movement of the clothes on that side of the tub in the reverse direction when

the general direction of movement of the clothes is reversed.

4. A washing machine comprising an oscillatable tub in which the clothes are thrown back and forth from one end to the other as the tub oscillates, the walls of the tub converging toward the ends whereby the clothes are packed together as they are thrown into the ends, and means for giving the mass of clothes a movement of rotation about a vertical axis as they are thrown back and forth comprising a member on one side of the tub having an abrupt shoulder facing and adjacent one tapering end of the tub, and a member on the other side of the tub having an abrupt shoulder facing and adjacent the other tapering end of the tub whereby the abrupt shoulders will have a retarding effect on one side of the mass of clothes as they are packed together and about to leave the end of the tub.

5. A washing machine comprising an oscillatable tub in which the clothes are thrown back and forth from one end to the other as the tub oscillates, the walls of the tub converging toward the ends whereby the clothes are packed together as they are thrown into the ends, and means for giving the mass of clothes a movement of rotation about a vertical axis as they are thrown back and forth comprising a member on one side of the tub having an abrupt shoulder facing and adjacent the tapering end of the tub, whereby the abrupt shoulder will have a retarding effect on one side of the mass of clothes as they are packed together and about to leave this end.

6. A washing machine comprising an oscillatable tub in which the clothes are thrown back and forth from one end to the other as the tub oscillates, said tub having a substantially flat bottom whereby the clothes slide easily from one end to the other, and means for giving the mass of clothes a movement of rotation about a vertical axis as they slide back and forth comprising a member on one side of the tub having an abrupt shoulder adjacent to and facing one end of the tub and a member on the other side of the tub having an abrupt shoulder adjacent to and facing the other end of the tub whereby the abrupt shoulders will have a retarding effect on the mass of clothes as they are packed together at the end of the tub and about to leave the end.

In witness whereof, I have hereunto subscribed my name.

ALFRED SWENSEN.
